UNITED STATES PATENT OFFICE

JAMES P. HOOPER, OF RUXTON, MARYLAND, ASSIGNOR TO WM. E. HOOPER & SONS COMPANY, OF BALTIMORE, MARYLAND, A CORPORATION OF MARYLAND

GOLF BAG

Application filed April 30, 1928. Serial No. 273,815.

The necessity for an exceptionally light golf bag, particularly for use by players not attended by caddies, has been generally recognized and such bags, known as week-end bags 5 on account of the additional difficulty incident to obtaining caddies over the week ends when there are a large number of players on the links, have been manufactured and become generally recognized as a commercial 10 article by dealers and players.

While the heavier bags are provided with longitudinal reinforcing members and stiffening means at the ends so that they can be stood on end with or without other lateral 15 support, thus retaining the clubs in position, the extremely light bags especially adapted to be carried by the player, i. e., bags of the so-called week-end type, are made of light fabric, the reinforce being omitted to reduce 20 the weight. These bags are subject to the difficulty that when an attempt is made to stand them upright with the clubs in position in the bag they are apt to collapse accordion-wise, releasing the clubs. For this reason 25 the so-called week-end bag is of advantage only on account of its lightness. As a holder for the clubs it is quite inferior to the heavier bags, as it must be held suspended by the strap or laid flat to avoid collapsing.

30 The present invention relates to a golf club bag which is as light as, or which exceeds so slightly in weight the typical week-end bag as to serve all the purposes of the latter. It is, therefore, available for all purposes for which the former product is used 35 and it possesses at the same time amply sufficient stiffness so that it serves all the purposes of the heavily stiffened and reinforced bags which may be stood upright, holding 40 the clubs in position without any tendency to collapse, as described in connection with the previously known week-end bags.

The bag which is the subject of the invention, while it is made of a fabric substantially 45 as light as that used for the flimsy bags previously constructed for this purpose, contains no longitudinal or lateral stiffening members corresponding to the stiffening or reinforcement of the heavy bags, the stiffening 50 feature in the present instance resulting

from the use of a stiffening fiber. This is shown in the form of a wire enclosed within the yarn or thread of which the fabric is woven.

In the accompanying drawings I have 55 illustrated a bag embodying the features of my invention in the preferred form. I have also illustrated in detail a fabric and reinforce adapted to the production of the desired result.

60 In the drawings:

Figure 1 is an elevation of the bag constructed in accordance with the invention in the preferred form.

Figure 2 is a section on the line 2—2 of 65 Figure 1.

Figure 3 is an elevation corresponding to Figure 1 showing a small fragment of the bag on an enlarged scale.

Figure 4 is an elevation of a fragment of 70 the preferred fabric for this purpose, likewise on an enlarged scale.

Figure 5 shows a short length of the reinforcing member enclosed in the yarn in accordance with the preferred form of the invention.

75 Referring to the drawings by numerals, each of which is used to indicate the same or similar parts in the different figures, the bag of the invention, in the preferred form as shown, consists of an elongated receptacle 1 open at the top at 2 and closed at the bottom at 3, as indicated. This bag is shown as provided with a shoulder strap 4 in accordance with the regular practice in the construction 80 of golf bags.

85 An important feature of the invention consists in the production of the bag as an exceedingly light structure which retains its form in upright and in all positions without collapsing and without the use of heavy longitudinal or lateral reinforcing members. To this end the material of which the bag is made is textile or suitable fibrous material 90 preferably spun into yarn or threads 6 and woven or otherwise formed into a fabric or other webbing or sheets 5, which is interwoven with fine reinforcing and stiffening means 95 8. A wire which is conveniently available for this purpose is known as music wire.

100

In the form of the invention shown, this reinforcing and stiffening wire 8 is enclosed in textile fibers forming reinforced yarn 12 which comprises a portion of the yarn used in the fabric 5 as illustrated in Figure 5. This may be most easily accomplished by spinning the yarn about the wire or otherwise wrapping the drawn and partially spun sliver or mat 9 of fibers about the wire 8.

10 In the form of the invention shown, the sides of the bag are formed of a tubular portion 10 which may be bound at the top at 11 surrounding the opening 2 and closed at the bottom by means of the bottom member 3 and this tubular portion 10, in accordance with the preferred form of the invention illustrated, may be woven on a circular loom, the reinforced yarn 12 containing the wire 8 serving as the weft or filling 7, the warp 14 being of the ordinary type though this exact arrangement of the fibers or the manner of weaving and constructing is not regarded as essential.

15 In accordance with the construction shown and described the weft or filling 7 extends around the tubular portion 10 of the bag in the form of a flat helix, the pitch of which is equal to the diameter of the weft. The bag formed of this fabric is, as already pointed 20 out, sufficiently stiff to stand upright. In fact, it retains its shape to much better advantage than the majority of heavy and reinforced bags and is at the same time practically as light as the collapsible bags already referred to.

25 I have thus described specifically and in detail a single preferred embodiment of the invention in order that the nature and manner of constructing the same may be fully understood, the terms herein being used descriptively rather than in a limiting sense, the scope of the invention being defined in the claims.

30 What I claim as new and desire to secure my Letters Patent is:

45 1. A golf bag composed of woven textile fabric, the fabric having warp threads extending in the direction of the length of the bag and weft threads extending around the bag, the weft threads comprising fine wire enclosed in textile fiber.

50 2. A golf bag comprising a tubular member of textile fiber closed at one end, the tubular member consisting of warp threads extending in the direction of the length of the tube and weft thread consisting of a wire enclosed in textile fiber and extending around the tubular member in the form of a helix.

55 3. A golf bag comprising a tubular member of textile fabric, said tubular member being closed at one end, the fabric consisting of threads extending in the direction of the length of the tube and threads extending around the tube, the latter comprising

stiffening members interwoven in and with the fabric.

Signed by me at Baltimore, Maryland, this 27th day of April, 1928.

JAMES P. HOOPER.
